(57) **CLAIM**

The ornamental design for a transport box, as shown and described.

DESCRIPTION

FIG. 2.1 is a front view of a first embodiment of a transport box according to the present invention;

FIG. 2.2 is bottom view thereof;

FIG. 2.3 is a top view thereof;

FIG. 2.4 is a left side view, the right side being a mirror image thereof;

FIG. 2.5 is a back view thereof;

FIG. 2.6 is a perspective view thereof;

FIG. 4.1 is a front view of a second embodiment of a transport box according to the present invention;

FIG. 4.2 is bottom view thereof;

FIG. 4.3 is a top view thereof;

FIG. 4.4 is a left side view, the right side being a mirror image thereof;

FIG. 4.5 is a back view thereof;

FIG. 4.6 is a perspective view thereof;

FIG. 6.1 is a front view of a third embodiment of a transport box according to the present invention;

FIG. 6.2 is bottom view thereof;

FIG. 6.3 is a top view thereof;

FIG. 6.4 is a left side view, the right side being a mirror image thereof;

FIG. 6.5 is a back view thereof; and

FIG. 6.6 is a perspective view thereof.

The broken lines shown in the drawings illustrate portions of

the transport box that form no part of the claimed design.

1 Claim, 18 Drawing Sheets
